UNITED STATES PATENT OFFICE.

JOSEPH ALVAH SCOTT, OF SEATTLE, WASHINGTON.

WATER-TUBE BOILER.

1,158,865.

Specification of Letters Patent.

Patented Nov. 2, 1915.

Application filed March 18, 1914. Serial No. 825,495.

To all whom it may concern:

Be it known that I, JOSEPH ALVAH SCOTT, a citizen of the United States, residing at Seattle, in the county of King and State of Washington, have invented certain new and useful Improvements in Water-Tube Boilers, of which the following is a specification.

This invention relates to water tube boilers, and especially to improvements in boilers such as shown and described in United States Patent No. 700,248, issued to me May 20, 1902.

The object of the invention is to improve the efficiency of boilers of this class and affording a construction which will facilitate the repair of the boiler by rendering the heating-tubes readily accessible for cleaning and for the removal and replacing of the tubes.

20 The invention is illustrated in the accompanying drawings, in which—

Figure 1 is a view partly in front elevation and partly in vertical transverse section of a boiler embodying the present invention. Fig. 2 is a vertical longitudinal section taken on line 2—2 of Fig. 1, and with parts omitted. Fig. 3 is a detail horizontal sectional view illustrating the disposition and means for securing the baffle-bars in place. Figs. 4 and 5 are vertical sectional views on lines 4—4 and 5—5 of Fig. 3. Fig. 6 is a fragmentary elevational view of Fig. 4 in the direction indicated by arrow. Fig. 7 is a similar view with respect to Fig. 5.

35 The reference numeral 10 designates a steam drum which is connected by an assembly or "bank" of inclined water-tubes, such as 12, with a mud drum 13 in each side of the furnace 14. The central portions of said 40 water-tubes are straight, or nearly so, and are provided with curved ends to enter the respective drums in directions approximately radially thereof and to which the tubes are connected by expanding their extremities in a well-known manner.

According to the present invention, the tubes of a bank are arranged in groups of two transverse rows with relatively narrow spaces A between the rows of each such 50 group. The spaces B between the groups,

however, are sufficiently wide to afford a convenient passage for tubes which are to be introduced in or withdrawn from the rows of tubes at either side of the spaces B. The spaces A and B serve, moreover, as 55 channels for the flow of the hot gaseous combustion products from the furnace 14 to a flue 15 provided at the outer side of a bank of tubes between a partition 21 and the adjacent wall 16 of the boiler casing. The 60 side walls 16 are desirably made removable to give access to the respective flues.

17 represents a smoke uptake connecting the flues at opposite sides of the boiler with the stack connection 18.

Intermediate its height a bank of tubes has its wide spaces B closed at the outer ends of the latter by means of bars 19 which are triangular or of an arcuate shape in horizontal section so as to extend into said spaces 70 and bear upon the tubes at each side of the same. Said bars are held in juxtaposition with the tubes by means of a rail 20 at the bottom and an overlapping edge of a partition 21 at the top. The rail 20 is secured by 75 bolts 22 to stirrup plates 23 which are positioned against the remote sides of the adjacent tubes (Fig. 3) and extend through holes provided in the respective bars. By such devices the bar at each of the bolts 22 is 80 supported by the latter. The remaining bars are supported by bolts 24 which engage in holes provided therefor in the bars and the rail.

All of the aforesaid bolts are screw-threaded at their outer ends for engagement with nuts 22¹ and 24¹. To prevent the rotation of the bolts 24 when screwing on or withdrawing the nuts, recesses 25 (see Figs. 4 and 6) are provided in the bars to receive 90 the bolt heads and are of such widths as to interfere with the turning of the heads. The turning of the other bolts 22 may be prevented by having the heads of the same encounter offset portions, as 23¹, of the stirrup plates.

A partition 21 is detachably secured in place by means of screw-bolts 26 engaging in the drum at the top and to stirrup plates below. Said partitions are, moreover, desir- 100

ably provided with perforations 27 to afford direct and relatively small passages there-through from the upper portion of the furnace into the flues 15 so as to establish a general outward movement to the hot gases which ascend into the space between said partitions prior to the descent of the main body of the gas which enters the flues from below.

10 In operation, the hot gases from the furnace enter the spaces about the various tubes to heat the same for the generation of steam; the hotter gases, however, ascend into the space unoccupied by the tubes between the 15 partitions, but through the office of such partitions and the suction created by the chimney draft, the hot gases are caused to descend to mingle with the hot gases within the spaces between the tubes and subjacent to the 20 partitions upon each side of the boiler. By reason of the communication between the wide spaces B and a flue 15 being closed by the bars 19, the exits for the smoke or gases to such flue are effected principally through 25 the narrow spaces A, resulting in rapid out-flowing currents therein, which creates a better circulation of the hot gases among the various tubes. It is thus seen that the partitions furnish receptacles, so to speak, about 30 the upper ends of the tubes in which the hotter gases, subject to the relatively small currents which escape through the perforations 27, are entrapped in their travel to the flues to afford time for the delivery of a large 35 portion of the heat from the gases to the drum 10 and the upper ends of the tubes, while a large part of the remainder of the heat of the gases, in their flow to the flues, is to a great extent delivered to the lower 40 portions of the tubes.

The advantages of disposing the tubes to provide the alternate wide spaces are two-fold—first, to furnish more room for the distribution of the hot gases among the 45 tubes; and secondly, to provide spaces whereby tubes, upon occasion, may be conveniently removed from and replaced in every row of either bank.

What I claim as my invention, is—

50 1. In a boiler of the class described, in combination, a casing having a stack connection at its top, a furnace within the casing, a steam drum above said furnace, partitions extending downwardly at opposite 55 sides of said drum and in spaced relations to the side walls of the casing to provide a flue between each partition and the adjacent side wall of the casing, said flues communicating from above with said stack 60 connection and with the furnace at a distance below said drum, mud drums at each side of said furnace, banks of tubes respectively connecting said mud-drums with the steam drum and extending through the space

between said partitions, each of said banks 65 of tubes being arranged to afford alternate wide and narrow spaces between the rows of tubes thereof and bars removably connected to said partitions for closing the wide spaces between said rows of tubes for a distance be- 70 low the adjacent partitions.

2. In a boiler of the class described, in combination, a casing provided with a chimney connection, a furnace within the casing, a steam drum, perforated partitions in 75 spaced relations with the side walls of the casing, and serving therewith to afford at each side of the drum flue connections between the boiler furnace and said chimney connection, through the perforation of said 80 partitions and also by the passages obtaining below the lower ends of the latter, said partitions also serving with said drum to provide the top of said furnace, a mud drum at each side of the furnace, tubes entering 85 the steam drum between said partitions and connected with both of the mud drums.

3. In a boiler of the class described, in combination, a steam drum, mud drums, a bank of tubes connecting said steam drum 90 with each of the mud drums, said banks of tubes comprising rows positioned to afford alternate wide and narrow spaces between said rows, a partition extending downwardly from the steam drum to inclose the 95 upper ends of both banks of tubes, bars removably secured to the plates and closing the wide spaces between the rows of tubes for a distance below the respective partition, and a rail secured to said bars and serving 100 to secure the latter in fixed spaced relation.

4. In a boiler of the class described, in combination, a casing having removable side walls, a furnace, a steam drum disposed above the furnace, mud drums at opposite 105 sides of the furnace, banks of water-tubes connecting the steam drum with the mud drums and comprising groups of tubes with relatively wide spaces between the adjacent 110 groups of each bank, partitions arranged with respect to said casing to afford upflow flues at the opposite sides of the boiler, said partitions being perforated, whereby a portion 115 of the hot gases ascending from the furnace into the space between the partitions may escape through such perforations into said flues while the remainder of such gases is caused to flow downwardly in all the spaces among the tubes, and bars depending from the respective partitions serving to direct such downflowing gases to escape to the flues principally through the spaces obtaining within the aforesaid groups of pipes.

5. In a boiler of the class described, in combination, a casing, a furnace within the 125 casing, a steam drum directly above the furnace, mud drums at opposite sides of the furnace, banks of tubes connecting the steam

and mud drums, and perforated partitions extending downwardly from the steam drum at the outside of each of said banks of tubes and constituting with the adjacent side walls 5 of the casing opposing walls of upflow flues, the perforations of said baffle-plates serving for the passage of a portion of the hot gases to said flues while the remainder of such

gases enter the lower ends of the flues by diving under the respective partitions.

Signed at Seattle, Wash., this 7th day of March, 1914.

JOSEPH ALVAH SCOTT.
